UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A DOMINO-SUGAR TRAY.

43,109.

Specification for Design.

Patented Oct. 8, 1912.

Application filed June 24, 1912. Serial No. 705,664. Term of patent 14 years.

To all whom it may concern:

Be it known that I, ANDREW J. SANFORD, a citizen of the United States, residing at Newark, county of Licking, State of Ohio, have invented a new, original and ornamental Design for Domino-Sugar Trays, of which the following is a specification, reference being had to the accompanying drawing, forming a part thereof.

The figure is a perspective view of a domino sugar tray showing my new design.

I claim:

The ornamental design for a domino sugar tray, as shown.

ANDREW J. SANFORD.

Witnesses:

JOHN M. SWARTZ,
JOHN R. RON.
